188,493

PORTABLE ELECTRO-MAGNETIC CRACK DETECTING TOOL

George H. Olcott, 128 Hubbard St., Allegan, Mich.

Filed Mar. 2, 1959, Ser. No. 54,811

Term of patent 14 years

(Cl. D26—1)

Figure 1 is a front elevation view of a portable electro-magnetic crack detecting tool showing my new design;

Figure 2 is an end view thereof;

Figure 3 is a top view thereof;

Figure 4 is a bottom view thereof; and

Figure 5 is a perspective view thereof.

I claim:

The ornamental design for a portable electro-magnetic crack detecting tool, as shown.
